CLAIM

I claim the ornamental design for an arm band case for portable electronic device, as shown and described.

DESCRIPTION

FIG. 1 is an enlarged front perspective view of an arm band case.

FIG. 2 is an enlarged rear perspective view of the arm band case.

FIG. 3 is a front view of the arm band case.

FIG. 4 is a bottom view of the arm band case.

FIG. 5 is a top view of the arm band case.

FIG. 6 is a left side view of the arm band case, the right side view being a mirror image thereof; and,

FIG. 7 is a rear view of the arm band case.

The broken lines depict environment and form no part of the claim.

1 Claim, 3 Drawing Sheets
